UNITED STATES PATENT OFFICE.

THOMAS F. HART, OF LYNN, MASSACHUSETTS, ASSIGNOR TO HAMEL SHOE MACHINERY COMPANY, OF LYNN, MASSACHUSETTS, A CORPORATION OF MASSACHUSETTS.

RIB TIGHTENER FOR GEM INNERSOLES.

Application filed May 19, 1917. Serial No. 169,674.

To all whom it may concern:

Be it known that I, THOMAS F. HART, a citizen of the United States, and resident of Lynn, county of Essex, Commonwealth of Massachusetts, have invented an Improvement in Rib Tighteners for Gem Innersoles, of which the following description, in connection with the accompanying drawings, is a specification, like characters on the drawings representing like parts in each of the several views.

This invention relates to mechanism for operating on reinforced innersoles for boots and shoes of the type commonly known as Gem innersoles, and is particularly intended to perform the operation of pressing the reinforce material closely into the angle of the rib thereby causing such material to adhere firmly to the leather of the innersole in the angle, this pressing of the reinforce material being performed by a tamping or hammering action and being commonly termed "rib tightening." A prime object of the invention is to provide a mechanism of this kind capable of great rapidity and flexibility of operation and permitting accurate and perfect manipulation for tightening the rib and pressing home the canvas layer even up to the extreme points of very pointed innersoles such as found in the current styles of ladies' shoes. The mechanism to be described is especially adapted for this last named purpose by reason of having a free rotating ball bearing table constituting the work rest in conjunction with a vibrating tamping tool or member operative at the inner side of the rib in cooperation with a driven presser disc operative to press home the canvas into the corner at the outer side of the rib. The invention also has to do with improved features of mounting and connections whereby the vibrating tamping tool is moved automatically out of the way upon a depression of the table for the insertion of work, without disturbing the operative connection of said vibrating tool or otherwise interfering with the continuity of operative movement. A still further object is to provide an improved construction of free rotating ball bearing table constituting the work rest in combination with a driven rib tightening disc operative on the outer edge of the rib and a vibrating obliquely mounted tool operative on the inward side of

the rib. The foregoing and other objects and advantages of the invention will more fully appear from the following detailed description, and the distinctive features of novelty will be pointed out in the appended claims.

Referring to the drawings:

Fig. 1 is a side elevation showing the essential portions of a machine constructed in accordance with my invention, a part thereof being broken away and another part in section;

Fig. 2 is a detail plan view of the work holding table;

Fig. 3 is a front view of the machine with a part of the base broken away;

Fig. 4 is a partial side elevation corresponding to Fig. 1 but showing the operative parts in action on a work piece; and

Fig. 5 is a partial side view showing the relation of parts when the table is depressed to receive a fresh piece of work.

A suitable pedestal and base frame work is indicated at 10 having spaced apart upstanding bearing posts 11, 12 on the top thereof in which is journaled a horizontal shaft 13 which constitutes the drive shaft of the machine and which is equipped with a suitable drive pulley 14 and a hand or balance wheel 15. This shaft has fixed thereon a worm 16 in driving engagement with a worm wheel 17 fixed at the upper end of a shaft 18 journaled vertically in bearings 19 of the frame work, this shaft having fixed at its lower end a bevel skew gear 20 in driving engagement with another skew gear 21 fixed on a shaft 22 journaled in bearings 23 of the frame to extend obliquely upward toward the front of the machine, this shaft having fixed at its top end a feed wheel 24. This wheel 24 is beveled and serrated on its lower edge, such bevel being at such an angle with reference to the inclined mounting of the shaft 22 that the outer lower edge of said beveled face is substantially horizontal and vertically opposite the inner edge portion of a rotatable table 25. The table 25 also has its edge portion serrated as indicated at 26 and this table is mounted for free rotation on a support 27, having preferably a ball bearing rest 28 on said support so as to permit the greatest freedom of movement. The support 27 is carried at the upper end of a post 29 vertically slidably in spaced apart bracket bearings 30 extending at the

front of the frame work. This table support is normally held yieldingly at an upper limit of movement which is determined by a collar 31 adjustably fixed thereon, by a coil 5 spring 32 encircling the same and reacting between the lower bearing element 30 and a cross pin 33 on said post. The table thus held may be depressed for the insertion or manipulation of work by a connection 34 10 to a suitable treadle (not shown). At 35 is indicated a vibratory tamping tool or hammer which as herein shown extends obliquely to the surface of the work table and has its operative extremity adjacent the rear edge 15 of said table, this tool being carried by a holder comprising a bell crank lever having arms 37, 39 upon the former of which the tool is adjustably mounted by means of a bracket 36. This bell crank is fulcrumed in 20 a bearing block 38, and its arm 39, which extends vertically, is provided with a roll at its free extremity arranged to engage in the cam groove 40 of a cam 41 which is fixed in the forward end of the shaft 13. As herein 25 shown the tool and the axes of the work table and feed wheel all lie in substantially the same plane whereby the area of contact is reduced to a minimum, which is of great importance in operating upon extremely 30 pointed soles.

The bearing block 38 upon which is fulcrumed the bell crank, above described, is carried at the forward end of a bar 42 which is mounted to slide horizontally in 35 a suitable bearing in the frame, and which is normally urged in a rearward direction by means of a coil spring 43 surrounding the bar and having one end bearing against the frame and the opposite end against a 40 collar 44 fixed upon the end of the bar. An adjustable stop pin 38^a is carried by the block 38 and is arranged to engage a fixed seat on the frame whereby the degree of rearward movement of the bar 42 under 45 the action of spring 43 may be determined.

The bar 42 being shown as round, is kept from turning by having a lug 45 thereon slidably guided in a slot 46 of the frame. In accordance with my invention means is 50 provided whereby as the table is depressed for inserting a new piece of work, the tamping tool 35 is simultaneously swung upwards and outwards so as to afford ample clearance. For this purpose I provide a 55 bell crank lever fulcrumed at 47 to the frame and having the end of one arm 48 thereof engaging the rear side of the bearing block 38, the other and horizontally extending arm 49 of said lever being provided 60 with an adjustable pin 50 engaging the lower side of the table support 27.

It may now be understood that upon the table being depressed by the treadle connection 34, the tamping tool will be swung 65 upward and outward as seen in Fig. 5, and

an innersole I may be placed on the table, the collar 31 having been adjusted according to the thickness of the batch of innersoles to be handled so that the table is permitted to rise just far enough to bring the feed 70 wheel 24 into action. Then, the stop screw 38^a having been likewise set in adjusted position so that the tamping tool 35 will operate at the correct range for the particular innersole stock in hand, the innersole 75 may be presented to the action of the feed wheel 24 and tamping tool 35 so that the canvas will be pressed tightly and firmly into the corners of the rib at each side, the required feed movement to reach all parts 80 of the rib being easily and rapidly obtained since the stock is resting on the ball bearing table 28. As has been above noted, the fulcrum for the tool holder constituted by the arms 37, 39 is movable in a forward and 85 rearward direction, and may be considered as constituting a floating bearing for said holder. By this arrangement not only is an automatic raising of the tool 35 upon depression of the table secured, but there is also provided a cushioning of the blow of the tool 35 during normal operation. This latter action may be better understood by considering that if the point of the tool is 90 prevented in any manner from reaching its normal downward limit of movement under the action of its operating cam, the tool holder may swing bodily about its point of engagement with the cam, due to the fact that its fulcrum is free to move in 95 a forward direction against the action of spring 43. Such action of the tool is very desirable in this type of machine as in the event that the tool 35 is improperly set or 100 the reinforce material is wrinkled or bunched in the channel, the tool if rigidly held might be broken or if the mechanism itself should not be damaged then the tool might be forced through the stock thereby 105 spoiling the latter. According to the present arrangement the spring 43, together 110 with the floating bearing for the levers 37, 39, perform the function not only of permitting separation of the tool and table during introduction of the work, but also of allowing the tool to resiliently accommodate itself to the thickness of the work. It may also be noted that by means of adjusting screw 38^a and the spring 43 the 115 initial position of the tool 35 may be determined at the will of the operator.

I attach a special importance to the co-operative arrangement of the free moving rotating table in conjunction with the vibratory tamping tool acting on the inner side of the rib, i. e., at the front or outer side of the machine, since thereby it is possible to work up into the extreme end of pointed innersoles much more satisfactorily and without mutilating the rib, than is possible 120 125 130

in other types of construction known to me. I do not desire to be limited to the precise structural details herein exhibited since these may be embodied in other forms with-

5 out departing from the essential attributes of the invention and I therefore desire the present embodiment to be considered as illustrative and not restrictive, and refer to the appended claims rather than to the foregoing description to indicate the scope of 10 the invention.

Having described my invention, what I claim as new and desire to secure by Letters Patent is:

15 1. A machine of the class described having, in combination, a work support mounted for free rotation about a substantially vertical axis, a feed wheel providing a peripheral work-engaging surface substantially parallel to the surface of said work support and spaced therefrom, means for imparting rotary movement to said feed wheel, a tamping tool supported for movement in a plane substantially perpendicular to said support, and means for vibrating 20 said tool in said plane.

25 2. In a shoe machine, in combination, a disc-like work support mounted for free rotation about a substantially vertical axis, a feed wheel mounted for rotation about an axis inclined to the vertical, said wheel having a serrated, peripheral surface disposed substantially parallel to the upper surface of said work support, means for imparting 30 a continuous rotary movement to said feed wheel, a tamping tool mounted for reciprocation toward and from said work support and means for reciprocating the said tool.

35 3. A machine of the kind described, comprising a work table mounted for rotation and for bodily movement into and away from an operative position, a feed wheel mounted in inclined relation to said table and adjacent a peripheral portion thereof 40 when said table is in operative position, means for driving said wheel, and a tamping tool mounted and connected for vibration in a plane substantially perpendicular to said table said tamping tool having a 45 mounting connected to swing said tool away from the working point as said table is lowered to afford clearance for inserting a work piece.

50 4. A machine of the class described having, in combination, a disc-like work table, means for supporting said table for free rotation about, and for bodily sliding movement along a substantially vertical axis, a rotatable feed wheel of a diameter relatively smaller than the table and mounted to turn about an axis inclined to the vertical, said wheel having its peripheral surface spaced from but adjacent the upper surface of said table and near one edge 55 thereof, means for driving said feed wheel,

and a tamping tool constructed and arranged to vibrate in a plane containing both of said axes.

5. A shoe working machine having, in combination, a disc-like work table mounted for free rotation about a substantially vertical axis and for bodily movement longitudinally of said axis, a feed wheel mounted to rotate about an inclined axis and having its peripheral surface normally closely adjacent one edge of said table, means for rotating said feed wheel, a tamping tool, means for reciprocating said tool toward and from said table, and means for resiliently adjusting the initial position of 75 said tool relatively to the surface of the table.

6. A machine of the kind described, comprising a table mounted for free rotation and also for bodily movement to and from a working position, a feed wheel mounted in inclined relation to said table and adjacent an inner peripheral portion thereof when the table is in working position, means for imparting a rotary movement to said feed wheel, a tamping tool mounted and connected for vibration in a plane substantially perpendicular to said table and in a direction inclined thereto, and a movable 80 mounting for said tool connected to be moved with the movement of said table whereby said tool is swung outward and away from said table and from said feed wheel as the table is moved from working position, to afford clearance for inserting 85 a work piece.

7. In a shoe machine, in combination, a work support, a tool having a working stroke toward and from said support, means for imparting a vibratory movement to said tool, and devices for simultaneously moving said support and tool from normal operative position to permit ready insertion of the work therebetween.

8. In a shoe machine, in combination, a 110 work table, a work feed element located relatively to said table to permit its engagement with work resting thereon, a tool mounted for reciprocation toward and from said table and in a plane substantially perpendicular to the surface thereof, means for reciprocating said tool, and devices for simultaneously moving said table and tool in opposite directions to facilitate insertion of the work.

9. In a machine for use in the manufacture of shoes, in combination, a vibratory tool, a holder for said tool comprising a bell crank lever, and means for supporting and actuating said lever, so constructed and arranged that during normal operation said lever operates as a lever of the first order but under abnormal conditions may operate as a lever of the third order.

10. A machine of the class described hav-

ing, in combination, a work support movable toward and from operative position, a vibratory tamping tool constructed and arranged to deliver a rapid succession of blows 5 to a piece of material supported upon said table, movable means for supporting said tool and a connection between said means and the work table whereby as the table is moved to and from operative position a 10 simultaneous adjustment of the tool with reference to its normal working position is effected.

11. In a shoe machine, in combination, a table constituting a work support mounted 15 for bodily movement into and out of operative position, a vibratory tamping tool constructed and arranged to deliver a series of blows against a piece of material supported upon said table, movable means for 20 supporting said tool, connections between said movable means and the work table whereby movement of the latter is transmitted to the former, and manual means for adjusting an element of said connections.

25 12. A shoe working machine having, in

combination, a work supporting table mounted for movement toward and from operative position, a vibratory tamping tool, means for imparting a reciprocatory movement to said tool in a plane substantially perpendicular to said table, a movable support upon which said tool is pivotally mounted, and a lever having its opposite extremities engaging said support and said table respectively whereby movement of the table is 30 transmitted to said support.

13. A shoe machine having, in combination, a depressible work table, a lever, a tool carried by one arm of said lever in cooperative relation to work supported on said 40 table, a cam, a follower therefor carried by the other arm of said lever, a movable fulcrum for said lever, and means for simultaneously depressing said work table and moving said fulcrum whereby said table and 45 tool are separated to permit insertion of work.

In testimony whereof I have signed my name to this specification.

THOMAS F. HART.
